SANDING MACHINE

Filed May 14, 1927

UNITED STATES PATENT OFFICE

FREDERICK H. JOHNSON, OF DETROIT, MICHIGAN

SANDING MACHINE

Application filed May 14, 1927. Serial No. 192,473.

This invention relates to a polishing or sanding tool and more particularly to an electrically driven belt type tool which may be manually supported.

5 It is an important object of my invention to provide a light weight device which will develop sufficient power to operate a polishing or sanding member directly driven by a rotating magnetic field.

10 More specifically stated the invention consists in driving a continuous polishing or sanding belt by the use of an induction motor; the rotatable member of which constitutes the belt pulley.

15 Another object of the invention is to provide a housing adapted to be manually supported having a pair of relatively adjustable primary windings carried thereby adapted to produce a rotating magnetic field which 20 solely effects rotation of belt pulleys supported by the housing.

25 Other objects and advantages will more fully appear from the following description taken in connection with the accompanying drawings, in which:

Fig. 1 is a side elevation of my improved device, with the belt backing shoe shown in section.

30 Fig. 2 is a plan view of Fig. 1, parts being broken away and parts shown in section.

Fig. 3 is a sectional view thru the stationary primary windings and the rotatable pulley; and

35 Fig. 4 is a side view of the adjustable support for one of the pulleys.

Referring to the drawings, wherein a preferred form of my invention has been illustrated, a housing 10 is shown provided with a rear handle 12 and a forward handle 14 extending at right angles to the rear handle 12. Suitable electrical conductors 16, adapted to be connected to any convenient source of electrical energy, are extended thru the forward handle 14 across the top of the housing 10 into a raised portion 18 to which is secured the rear handle 12. A cover 20, detachably secured to the portion 18, covers the conductors 16 leading to a switch 22 in the rear handle 12.

50 The housing 10 comprises a top portion

24 and a side portion 26. The side portion 26 is provided with a split boss 28 which receives a support 30 for one of the pulleys and a boss 32 which receives an adjustable support 34 for the other pulley. The support 30 is provided with a portion 36 which is received in the split boss 28 and clamped therein by a screw 38 engaging flanges 40 of the boss to pinch it around the portion 36.

55 A flange 42 is adapted to form an end plate for the mechanism carried by the support and engages the side portion 26 to position the support axially. A belt pulley 44 is secured to a shaft 46 rotatably supported in an inner boss 48 of the support 30. A sleeve 50, fixed to the boss 48, surrounds the shaft 46 and has its outer periphery provided with a plurality of steel plates 52 with windings 54 around portions thereof to form a plurality of poles 56, constituting the primary 60 or stator of an induction motor. A bearing 58 is mounted in the inner periphery of the sleeve 50 to take the radial load of the shaft and pulley. Mounted on the inner periphery of the pulley 44 are a plurality of steel plates 60 held together by rivets 62 or any means adapted to form therebetween poles 64 which constitute the secondary or rotor of an induction motor.

65 The rotor is provided with fins 66 which act as fan blades to cause a circulation of air thru openings 68 to cool the parts of the primary. The sides of the openings 68 are tapered to draw air out of the primary windings. An alternating current, preferably a three phase 180 cycle, is

70 supplied to the windings 54, thru the conductors 16, switch 22 and leads 70, producing an inherent revolving magnetic field about the primary, the action of which effects rotation of the secondary without sup-

75 pllying an electrical current thereto as in the use of a commutator thereby reducing the weight. The weight has been further re-

duced by making the primary the inner or 80 stationary part and the secondary the outer or rotatable part. By this arrangement the diameter of the air gap has been increased

85 thus increasing the power of a small motor, a factor of the horsepower being the di-

90

95

100

ameter of the air gap squared times the length of the primary.

It has been found that a single pulley rotated in the manner develops sufficient power to drive a polishing or sanding belt around an idler pulley which may be substituted for the one shown as a driving pulley. The pulleys are shown interchangeable, one rigidly supported on the housing 10 and the other adjustably carried by the adjustable support 34. The portion 36 is provided with apertures 74 which receive a pin 76. An arm 78 is fitted over the portion 36 and is pivoted between a bifurcated portion 80 of the support 34. The outer end of the arm 78 is resiliently held as by a spring 81 against a screw threaded stop 82 carried by the support 34. By this arrangement the pulley may be angularly positioned to cause the belt 72 to run true on the pulleys. The support 34 is longitudinally adjustable in the boss 32 to adjust the tension on the belt. It is resiliently held in one position by a spring 84 and positively held in the other direction by a threaded member 86 abutting against the boss 32. The support 34 has a projecting member 88 adapted to slide in an opening 90. The spring 84 is mounted on a cylindrical reduced portion 92 and is compressed between a shoulder 94 and the end wall of the opening 90. The reduced portion extends thru the end wall and is provided with screw threads to receive the screw threaded member 86. By turning the member 86 in one direction the support and pulley is drawn inwardly against the spring resistance and by turning it in the opposite direction the spring 84 urges the support and pulley in the opposite direction.

40 Detachably secured to the boss 32 or housing 10 is a shoe member consisting of a plate 96 to which is secured a felt pad 98. A rubber pad 100 is held between the plate 96 and pad 98. The outer or lower surface of the felt pad 98 is coated with graphite 99 to permit the belt 72 to easily slip thereon. The shoe is secured to the housing by screws 102 which may be removed to replace the shoe. The tool is supported on the shoe rather than the pulleys and the resilient belt backing permits the working surface to conform to the surface of the article being polished or sanded.

It will be understood that various changes may be made in the arrangement, combination and construction of the various parts of my invention without departing from the spirit thereof and it is not my intention to limit its scope other than by the terms of 60 the appended claims.

What I claim is:

1. In a device of the class described comprising a housing adapted to be manually supported, a pair of pulleys rotatably supported by said housing, a belt having an

abrasive surface around said pulleys, means for rotating one of said pulleys, a resilient shoe carried by said housing comprising an outer yieldable felt pad and an inner resilient rubber pad, said shoe being adapted to urge 70 said belt against relief irregularities on a piece of work with greater intensity than against surrounding regular surfaces.

2. In a device of the class described comprising a housing, a pair of pulleys rotatably supported by said housing, a belt having an abrasive surface around said pulleys, means for rotating one of said pulleys, a resilient shoe carried by said housing having a felt pad backed by a rubber pad, and a graphite 80 coating on the outer surface of said felt pad, said shoe adapted to urge a portion of said belt beyond its natural path of travel.

FREDERICK H. JOHNSON.
